CLAIM

We claim the ornamental design for a combined foot and calf massager, as shown and described.

DESCRIPTION

FIG. 1 is a top front perspective view of the combined foot and calf massager of the present invention.

FIG. 2 is a bottom rear perspective view of the combined foot and calf massager of FIG. 1.

FIG. 3 is a front elevation view of the combined foot and calf massager of FIG. 1.

FIG. 4 is a rear elevation view of the combined foot and calf massager of FIG. 1.

FIG. 5 is a side elevation view of the right side of the combined foot and calf massager of FIG. 1.

FIG. 6 is a side elevation view of the left side of the combined foot and calf massager of FIG. 1.

FIG. 7 is a top plan view of the combined foot and calf massager of FIG. 1; and,

FIG. 8 is a bottom plan view of the combined foot and calf massager of FIG. 1.

The broken lines shown in the drawings are for the purpose of illustrating portions of the combined foot and calf massager, which form no part of the claimed design.

1 Claim, 7 Drawing Sheets
